UNITED STATES PATENT OFFICE

CHRISTOPHER CANEPA, OF BRONX, NEW YORK

DESIGN FOR A CLOCK CASE

Application filed May 2, 1932. Serial No. 43,699. Term of patent 3½ years.

To all whom it may concern:

Be it known that I, CHRISTOPHER CANEPA, a citizen of the Kingdom of Italy, residing in the borough of Bronx, in the county of Bronx, State of New York, have invented a new, original, and ornamental Design for a Clock Case, of which the following is a specification, reference being had to the two accompanying drawings, forming part thereof.

In the drawings:

Figure 1 is a front view of a clock case showing my new design; and

Figure 2 is a side view of the same. The opposite side of the clock case bears ornamentation similar to that shown in Figure 2.

I claim:

The ornamental design for a clock case, as shown and described.

In testimony whereof, I affix my signature.

CHRISTOPHER CANEPA.
